UNITED STATES PATENT OFFICE.

ROBERT L. LYONS, OF WALTHAM, MASSACHUSETTS, ASSIGNOR TO THE FREDERICK OSANN COMPANY, OF NEW YORK, N. Y., A CORPORATION OF NEW YORK.

THREAD-CUTTING DEVICE.

1,246,965.

Specification of Letters Patent. Patented Nov. 20, 1917.

Application filed December 2, 1915. Serial No. 64,738.

To all whom it may concern:

Be it known that I, ROBERT L. LYONS, a citizen of the United States, and a resident of Waltham, in the county of Middlesex and State of Massachusetts, have invented certain new and useful Improvements in Thread-Cutting Devices, of which the following is a specification, reference being had to the accompanying drawings, forming part thereof.

This invention has reference to improvements in thread cutting devices for sewing machines and has for one of its objects the safeguarding of the cutter element and the 15 stitch forming devices from injury by or through the accidental actuation of the cutter mechanism during the operation of the stitch forming devices.

Another object of this invention is to so 20 construct a thread cutting device for a sewing machine that the cutter element shall be positively moved to a position out of the path or paths of the stitch forming device or devices at the initial operation of the 25 machine and before either of the stitch forming devices can strike the cutter element.

Another object of the invention is to improve the construction of the thread cutter 30 and its operating means.

Other objects of the invention will appear from the following description.

The invention consists in the novel construction of the thread cutter device and 35 its operating means and the combination therewith of the novel retractor or protector device.

The invention also consists in the means for preventing the accidental or unauthorized 40 operation of the cutter element at times.

The invention also consists in such other novel features of construction and combination of parts as shall hereinafter be more fully described and pointed out in the 45 claims.

Figure 1, represents a bottom plan view of parts of a sewing machine of known construction having the new improvements in thread cutting mechanism applied thereto.

50 Fig. 2, represents a cross sectional view of parts of the same as taken on line 2—2 Fig. 1.

Fig. 3, represents a detail sectional view of parts as taken on line 3—3 Fig. 1.

Fig. 4, represents a similar view as taken 55 on line 4—4 Fig. 1, and showing a loop of thread on the looper.

Fig. 5, represents a similar view taken on line 5—5 Fig. 1.

Similar characters of reference designate 60 corresponding parts throughout.

As shown in the drawings, in its preferred form, 6 represents the bed plate of a sewing machine of well known construction and of the variety known as a single thread machine but it is not intended by such showing necessarily to limit the use of the present invention thereby. This bed plate 6 has the needle passage 7 and, at its under side is supplied with the longitudinal members 8, 70 8 and with the transversely extending members 9 and 10. Journaled in a bearing of the member 9 is the looper shaft 11 which operates the usual looper 12, located beneath the needle passage 7, and said looper shaft 75 11 is driven in any well known manner through connections with the worm shaft 13 journaled in a bearing of member 10 and operated in the manner well known in this class of machines.

On the worm or cam shaft 13 is mounted the worm 14 and the protector disk or member 15 which latter is substantially circular in peripheral shape but has, cut out of its peripheral portion, the notch 16 having the 85 straight edge 17 and the inclined edge 18 in the nature of a cam which merges into the circular periphery of this disk as is shown in Fig. 2, the direction of rotation of this disk being indicated by its arrow. 90

Journalized on the stud 19 secured to the under side of bed plate 6, is the disk 20 having the gear member 21 which is driven from the worm 14. This disk 20 has a circular periphery or path 22 having at one 95 point the depression or clearance 23 the purpose of which will be hereafter explained.

At the under side of the bed plate 6 is the stud 24 on which is pivoted the cutter operating and controlling lever 25 which has 100 the slot 26 at its free end. Mounted on this lever 25 is the member 27 having the follower or rider rod 28 adapted to ride against the periphery or way 22 of disk 20 during

certain operations of the machine and with which the clearance 23 of said disk is brought into registry at or about the time the rotation of the looper 12 ceases as will 5 hereafter be described.

Adjacent the free end of lever 25 is mounted, at the under side of bed plate 6, the casting 29 which has the slot 30 and the way 31 in which the cutter slide 32 is slideable, said 10 cutter slide is pressed in one direction by its spring 33 and may be actuated in the other direction by the lever 25 with which said slide is connected by means of its pin 32' secured in said slide, extending through slot 15 30 and engaged in slot 26 of said lever. On said slide 32 is mounted the cutter member 34 having the cutting blade 35 of slightly 20 hook shape and having cutting edges *a*, *b* and *c* said blade 35 being adapted to be moved between the bed plate 6 and the 25 looper 12 when said looper extends approximately parallel to said bed plate as is shown in Fig. 1 of the drawings.

Slidably mounted with respect to the bed 25 plate 6 is the rod 36 which may be depressed at times by means of the connection 37 adapted to be operated in any desired manner to, at times, effect the depression of said rod 36 to cause the swinging of its related 30 bell crank 38 which is pivotally sustained by the stud 39, extending from one of the bed plate members 8, and pivotally connected with the cutter actuator 40.

The cutter actuator 40 has the bevel end 35 41 and the depressions or reduced portions 42 and 43 of which the former is adapted to afford clearance for shaft 13 while the latter depression is adapted to receive the cutter depression is adapted to receive the cutter actuator lever 25 and has the shoulder 40 44 which in one direction of movement of actuator 40 may engage and move said lever 25 under certain positions of the mechanism. This actuator 40 is slideable in a direction 45 transverse to the lever 25 and is normally sustained by the spring 45 for the purpose of effecting engagement of the depression 43 with said lever 25 and to permit, at times, the disengagement of these parts, such disengagement is accomplished, under movement of said actuator 40, in one direction, by the riding of its cam member 46 over the operating cam member 47 mounted on any suitable part of the machine.

Under normal conditions of the stitch 55 forming operation of the machine to form a group of stitches the cutter member 34 will preferably occupy the position shown in full lines in Fig. 1. At the completion of such sewing or stitch forming operation 60 the thread will extend as a loop *L* having the arms *x*, *y*, sustained in part by the looper 12 and extending upward, the arm *x* being in the path of the edge *c* of the cutter 35 and preferably the thread will have the knot 65 *k* formed as is usual in this class of ma-

chines. At this time the protector disk 15 has been rotated with its shaft 13 to bring the notch 16 of said disk into registry with the cutter operating lever 25 and the disk 20 has been rotated through its driving connection with said shaft 13 until its clearance 23 is in position to receive the rider 28. The actuator 40 may now be operated by drawing down the slide rod 36 whereby, through bell crank 38, said actuator 40 is 70 shifted endwise in order that the shoulder 44 of said actuator may engage with and move said lever 25, such movement being permitted because of the fact that notch 16 of disk 15 is positioned to receive said lever 25 and that the clearance 23 of disk 20 is in 75 position to receive the rider 28.

Such swinging movement of lever 25 effects the sliding movement of the slide 32 and its cutter member 34 against the action 80 of spring 33 with the result that the edge *c* of the cutter 35 is drawn against the arm *x* of the thread loop *L* and may cut said arm. If, however, said arm *x* of the loop is not cut by edge *c* on such retractive movement 90 of the cutter member 34 said edge *c* rides against and passes said loop arm *x* and the cutter 34 is brought approximately to the position shown in dotted lines in Fig. 1. At or about this time the cam block 46 riding against its coöperating member 47 effects the forcing downward of the free end 95 of the actuator 40 to disengage the depression 43 of said actuator from lever 25 whereby said lever is free to be swung to its original position by or through the action of spring 33 in which movement the cutter member 34 is carried forward and the edge *a* of its cutter engages and cuts the loop arm *x*.

After the release of actuator 40 from lever 100 25 rod 36 is permitted to slide upward and spring 45 is then allowed to draw said actuator to its normal position to again receive lever 25 in its depression 43.

Ordinarily the action of spring 33 will 110 be sufficient to return slide 32, cutter member 34 and lever 25 to the position shown in full lines in Fig. 1, and it is desirable that the cutter member 34 should reach such position or at least be moved to a position out 115 of reach of the looper 12 before the looper has, in the next sewing operation, rotated to a point to strike the cutter 35 of said member 34. If, therefore, the action of spring 33 has not moved its slide 32 and 120 cutter member 34, or has not moved such parts sufficiently to return said parts to the safe position lever 25 will not be swung out of notch 16 of the protector disk 15. In this event, when the machine is again started, 125 the disk 15 will rotate with the shaft 13 in the direction indicated by the arrow of said disk and the cam edge 18 thereof will ride against the lever 25 and move said lever outward until the edge of said lever 25 is clear 130

of the periphery of the disk 15. This positive movement of lever 25 is effected during a partial rotation of shaft 13 with the result that the slide 32 is actuated and cutter member 34 is moved to the safe position before the looper 12 rotates sufficiently to strike the cutter 35.

By reference to Fig. 1 it will be noticed that disk 15 is of smaller diameter than the 10 disk 20, the purpose of disk 15 being primarily, by means of its cam edge 16, to effect a quick safety or resulting movement of lever 25, to move cutter member 34 to the safe position, and then to sustain such lever 15 25 in such position by the riding of the periphery of disk 15 against the edge of said lever, until disk 20 has been rotated sufficiently to carry its clearance 23 out of registry with the rider pin 28, the periphery 22 20 of this disk 20 then constituting a path or way to sustain this rider pin 28 throughout the sewing operation as the sewing operation is intended to be completed during a rotation of disk 20 or at least before its 25 clearance 23 is again brought into registry with the rider pin 28. By this construction the unauthorized or accidental swinging of lever 25 to effect movement of the cutter member 34 or its cutter 35 into the path of 30 the stitch forming devices during the operation of said devices is prevented.

It is obvious that the means for actuating lever 25 from its position of safety may differ considerably from the actuator 40 and 35 also that said lever actuating means need not necessarily be adapted to be manually operated.

While I have herein shown a specific construction of my improved safety cutter 40 mechanism it is not my intention thereby to limit my invention except as herein claimed.

Having thus described my invention I claim as new and desire to secure by Letters Patent.

45 1. A sewing machine comprising in combination with a stitch forming device having a looper and means for operating said device, a thread cutter mounted for movement into the path of movement of said looper, and means operating relative to said stitch forming device to move said cutter to a point of safety during the initial stitch forming movement of said looper.

2. A sewing machine comprising in combination with a stitch forming device having a looper and means for operating said device, a thread cutter mounted for movement into the path of movement of said looper, means to actuate said cutter and means operating relative to such looper to prevent the operation of said cutter during the operation of said looper.

3. A sewing machine comprising in combination with a stitch forming device having a looper and means for operating said

device, a thread cutter mounted for movement into the path of movement of said looper, actuating means for said cutter having a hold back, and means operated relative to said device and co-operating with said hold back to prevent the movement of said hold back during certain operations of said looper.

4. A sewing machine comprising in combination with a stitch forming device having a looper and means for operating said device, a thread cutter mounted for movement into the path of movement of said looper, means actuated by said operating means to move said cutter to the safe position, and other means in operative connection with said operating means to prevent the operation of said cutter approximately throughout the sewing operation.

5. A sewing machine comprising, in combination, a stitch forming device adapted to sustain a thread loop, a cutter member mounted for movement to cut said loop, a lever for operating said cutter, means for positively moving said lever in one direction, and other means for positively holding said lever in position when so moved, said lever moving means and lever holding means operating relatively.

6. A sewing machine comprising, in combination, a rotary looper, an operating shaft therefor, a member carried by said shaft and having a cam, a cutter mounted for movement relative to said looper, cutter operating means in operative relation to said cam, and means to prevent the retractive movement of said cutter operating means during a series of rotations of said looper.

7. A sewing machine comprising, in combination, a rotary looper, an operating shaft, connections for operating said looper from said shaft, a thread cutter member, a pivoted lever for operating said cutter member, and a disk mounted on said operating shaft and having a notch to receive said lever and cam for effecting movement of said lever from said notch.

8. A sewing machine comprising, in combination, a rotary looper, an operating shaft, connections for operating said looper from said shaft, a thread cutter member, a pivoted lever for operating said cutter member, and a pair of rotary members operated by said shaft, one of said members having a notch to receive said lever and a cam to effect movement of said lever out of said notch, the other said member co-operating with said lever to hold the same in an inoperative position.

9. A sewing machine comprising, in combination, a rotary looper, an operating shaft, connections for operating said looper from said shaft, a thread cutter member, a pivoted lever for operating said cutter member, a rider device carried by said lever, and

a pair of rotary disks of different diameters, the smaller of said disks mounted on said shaft and having a notch to receive said lever and the larger of said disks, driven 5 from said shaft having a way against which said rider may bear.

10. A sewing machine comprising, in combination, a rotary looper, an operating shaft, connections for operating said looper from said shaft, a thread cutter member, a pivoted lever for operating said cutter member, a rider device carried by said lever, a pair of rotary disks of different diameters, the smaller of said disks mounted on said 15 shaft and having a notch to receive said lever and the larger of said disks, driven from said shaft having a way against which said rider may bear, and a clearance to receive said rider at times.

11. A sewing machine comprising, in combination a rotary looper, an operating shaft, connections for operating said looper from said shaft, a thread cutter member, a pivoted lever for operating said cutter member, 25 a rider device on said lever, a rotary member driven from said shaft and having a peripheral way against which said rider may bear and a clearance to receive said rider at times, and means to operate said lever.

12. A sewing machine comprising, in com-

bination a rotary looper, an operating shaft, connections for operating said looper from said shaft, a thread cutter member, a pivoted lever for operating said cutter member, an actuator member releasably engaged 35 with said lever, means positively to return said lever to position when disengaged from said actuator, and other means positively to prevent the operation of said lever during the sewing operation.

13. A sewing machine comprising, in combination, a rotary looper, an operating shaft, connections for operating said looper from said shaft, a thread cutter member, a pivoted lever for operating said cutter member, a rider device carried by said lever, a pair of rotary disks of different diameters, the smaller of said disks mounted on said shaft and having a notch to receive said lever and the larger of said disks, driven from said shaft having a way against which said rider may bear, a spring sustained actuator having a recess to releasably receive said lever, coöperating cams on said actuator and the machine to effect release of said actuator from said lever under movement of said actuator, and means to operate said actuator.
